UNITED STATES PATENT OFFICE

HARRY C. VANTASSEL, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY-TRAFFIC-CONTROLLING APPARATUS

Application filed October 9, 1929. Serial No. 398,316.

My invention relates to railway traffic controlling apparatus, and particularly to apparatus of the type involving a fluid pressure operated switch and a signal governing traffic over the switch, both of which are controlled by manually operable levers located at a remote point.

One feature of my invention is the provision of means for indicating at such remote point whether or not the fluid pressure available for the operation of the switch is above or below a given value, using certain of the line wires which are employed for the control of the signal to give such indication.

15 I will describe one form of apparatus embodying my invention, and will then point out the novel features thereof in claims.

The accompanying drawing is a diagrammatic view showing one form of apparatus 20 embodying my invention.

Referring to the drawing, the reference character A designates a railway switch which is operated by a fluid pressure device C, and which device is supplied with fluid pressure through a pipe 4 from a source which is not shown in the drawing. Traffic over the switch A is governed by a signal B comprising a high speed arm 1, a medium speed arm 2, and a calling-on arm 3.

30 The switch A and the signal B are controlled by manually operable levers located at a remote point. In the drawing I have illustrated a lever F for the control of signal B, but the lever for the control of the switch A is not shown because it forms no part of my present invention.

35 Furthermore, the control of the arms 1 and 2 of the signal B is not illustrated because the means for controlling these arms, likewise, forms no part of my invention. I have, however, illustrated the means 40 for controlling the calling-on arm 3 by the lever F.

The calling-on arm 3 is controlled by a relay E. When this relay is de-energized, the calling-on arm is in "stop" position. When the relay E is energized, the calling-on arm is moved to the "clear" position by virtue of a circuit which passes from the upper terminal of a battery K, through front contact 8 of relay E, and the operating mechanism of the

calling-on arm 3 to the middle point of battery K. When the lever F is in its middle position, as shown in the drawing, a circuit for relay E is closed, which circuit passes from the upper terminal of battery K, through back contact 7-7^a of a relay D, winding of relay E, line wire 18, resistance 14, contact 11 or lever F, winding of a polarized relay H, and line wire 19 to the middle point of battery K. The current which flows in this circuit is of such polarity that it holds contact 17 of relay H open, and this current is limited in value by the resistance 14 so that the amount of current flowing in relay E is not sufficient to close the front contact 8 of this relay. It follows 55 that calling-on arm 3 then indicates "stop".

I will now assume that lever F is swung to the right. The circuit for relays E and H will then pass from the upper terminal of battery K, through back contact 7-7^a of relay D, winding of relay E, line wire 18, resistance 14, back contact 13 of a relay G, contact 10 of lever F, winding of relay H, and line wire 19 to the middle point of battery K. Resistance 14 is still included in the circuit, so 60 that relay E remains de-energized. If now the operator closes a push button 16, relay G will become energized by virtue of a circuit which passes from a battery 15, through the winding of relay G, push button 16, and contact 9 of lever F to battery 15. Relay G will then remain energized by virtue of a stick circuit which passes from battery 15, through the winding of relay G, front contact 12 of relay G, and lever contact 9 to battery 15.

65 The front point of contact 13 of relay G will now be closed, and lever contact 10 is also closed, so that resistance 14 will be excluded from the circuit for relays E and H. The amount of current flowing in this circuit will 70 then be sufficient to close front contact 8 of relay E, so that the calling-on arm 3 of signal B will be cleared. When lever F is restored to its normal position, the stick circuit for relay G will be opened at contact 9, so that 75 this relay will become de-energized, and the parts will be restored to the positions in which they are shown in the drawing.

If the lever F is swung to the left to clear 80 signals governing traffic in the other direction 100

over switch A, which signals are not shown in the drawing, the circuit for relays E and H will not be disturbed, because this circuit will then be completed through contact 11 of lever F.

5 The reference character L designates a pressure responsive device which is connected with the pipe 4 leading to the source of fluid pressure for the operation of switch A. This 10 device L comprises a diaphragm 5 controlling a contact 6 in such manner that the contact is open when the pressure available for the operation of switch A is normal, but becomes closed when this pressure drops below 15 its normal value. Contact 6 controls the relay D in such manner that this relay is energized or de-energized according as contact 6 is closed or open. The circuit for relay D will be obvious from the drawing. 20 Assuming that contact 6 becomes closed, relay D will become energized, whereupon, the circuit for relays E and H will then pass from the lower terminal of battery K, through front contact 7-7^b of relay D, winding of 25 relay E, line wire 18, resistance 14, lever contact 11, winding of relay H and line wire 19 to the middle point of battery K. The polarity of this current is such that the contact 17 of relay H will become closed, thereby 30 closing the circuit for an indication lamp I, which circuit is from battery 15, through contact 17 and lamp I to battery 15. The lighting of lamp I will indicate to the operator that the pressure available for the 35 operation of switch A has fallen below its normal value. The reversal of the polarity of the current supplied to the circuit for relays E and H will not, however, affect relay E.

40 It will be seen from the foregoing that I have provided means for indicating the condition of the fluid pressure available for the operation of switch A without the necessity for additional line wires between this switch and the remote point from which the switch 45 is controlled.

Although I have herein shown and described only one form of apparatus embodying my invention, it is understood that various changes and modifications may be made 50 therein within the scope of the appended claims without departing from the spirit and scope of my invention.

Having thus described my invention, what I claim is:

55 1. In combination, a fluid pressure operated railway switch, a signal governing traffic over said switch, a relay for the control of said signal and responsive in the same way to current of either normal or reverse polarity, an indicator, a relay selectively responsive to current of normal and reverse polarity for controlling said indicator, a circuit including said two relays in series, manually operable means for varying the strength 60 of the current in said circuit to affect said

signal controlling relay, and means responsive to the fluid pressure available for operation of said switch for changing the polarity of the current supplied to said circuit and to thereby affect the operation of said indicator controlling relay.

2. In combination, a fluid pressure operated railway switch, a signal governing traffic over said switch, a relay for the control of said signal and responsive to changes in the strength of the current with which it is supplied but not to reversals of the polarity of such current, a lever for the control of said signal, a relay associated with said lever and selectively responsive to current of normal or reverse polarity, an indicator controlled by said second relay, a circuit including said two relays in series, means associated with said lever for varying the strength of the current in said circuit to affect said signal, and means responsive to the fluid pressure available for operation of said switch for changing the polarity of the current supplied to said circuit and to thereby affect the operation of said indicator controlling relay.

3. In combination, a fluid pressure operated railway switch, a signal governing traffic over said switch, a relay for the control of said signal and responsive to changes in the strength of the current with which it is supplied but not to reversals of the polarity of such current, a lever for the control of said signal, a relay associated with said lever and selectively responsive to current of normal or reverse polarity, an indicator controlled by said second relay, a circuit including said two relays in series, means associated with said lever for varying the strength of the current in said circuit to affect said signal, a third relay associated with said switch for changing the polarity of the current supplied to said circuit, a contact for controlling said third relay, a source of fluid pressure for the operation of said switch, and a pressure responsive device connected with said source for the control of said contact.

In testimony whereof I affix my signature.
HARRY C. VANTASSEL.
